UNITED STATES PATENT OFFICE.

KATE HATCH, OF BROOKLYN, NEW YORK, ASSIGNOR OF ONE-HALF TO
CHARLES F. LANGHAAR, OF SAME PLACE.

BATHING-FORM.

SPECIFICATION forming part of Letters Patent No. 550,171, dated November 19, 1895.

Application filed April 9, 1895. Serial No. 545,104. (No model.)

To all whom it may concern:

Be it known that I, KATE HATCH, of Brooklyn, in the county of Kings and State of New York, have invented a new and Improved 5 Bathing-Form, of which the following is a full, clear, and exact description.

The object of the invention is to provide a new and improved bathing-form designed for the use of ladies while bathing in the surf, 10 river, lake, or other place, and arranged to protect and shield the upper front part of the body.

The invention consists of certain parts and details and combinations of the same, as will 15 be fully described hereinafter, and then pointed out in the claims.

Reference is to be had to the accompanying drawings, forming a part of this specification, in which similar letters of reference indicate 20 corresponding parts in both the figures.

Figure 1 is a perspective view of the improvement as applied, and Fig. 2 is an enlarged rear perspective view of the improvement.

25 The improved bathing-form is provided with a front A, made of a single piece of rubber or other suitable but pliable material, so as to fit snugly and conform to the upper part of the wearer's body, as plainly illustrated in Fig. 1. The front A is formed with pockets A' for supporting the bust, and the upper end of the said front is provided with shoulder-straps B B', made of the same material as the front A and adapted to hook upon 30 hooks C C', secured to rear extensions A² and A³, respectively, formed on the sides of the front A at the lower ends thereof.

The shoulder-straps B and B' are provided with longitudinal openings B² and B³, through 40 which extend loosely the side straps D and D', respectively, extending from the sides of the front near the upper ends thereof, so as to pass under the wearer's arms, to cross to the back, and to be attached to hooks E on the sides of the front, as is plainly illustrated 45 in Fig. 1.

Back straps F and F' extend from the extensions A² and A³ to pass through loops G and G', respectively, secured on the extensions A³ and A², respectively, as indicated in 50 Fig. 2. The front ends of the back straps F

and F' are hooked upon hooks H, secured to the front A below the hooks E.

As indicated in the drawings, each of the straps is provided with a series of apertures, 55 one of which is adapted to engage the corresponding hook, so as to permit the wearer to draw the strap sufficiently tight to conveniently support the form on the wearer's body. Other suitable fastening means instead of 60 hooks and apertures may be employed.

When it is desired to use the garment, the straps D D' and F F' are disengaged from their hooks, so that the wearer can readily apply the form at the front upper portion of 65 the body and then fasten the shoulder-straps B B' upon their hooks and the side straps D D' and back straps F F' upon their corresponding hooks, so as to securely fasten the form in place.

Having thus fully described my invention, I claim as new and desire to secure by Letters Patent—

1. A bathing form comprising a front of pliable material provided at the opposite sides 75 of its lower end with the rearward extensions, the shoulder straps extended from the opposite sides of the upper end of the front, means for securing the shoulder straps to the rear extensions, connections between said lower 80 extensions, and the side or arm straps extended from the front, back through loops on the rear lengths of the shoulder straps and secured at their other ends to the opposite side of the front all substantially as and for 85 the purposes set forth.

2. A bathing form comprising a front having at its lower corners rearward extensions the shoulder straps having rear lengths extended longitudinally downward without 90 crossing and secured at their lower ends to their respective rear extensions the side straps extended from one side of the front, back and secured at their ends to the opposite side of the front, said side straps crossing each other 95 and the rear lengths of the shoulder straps diagonally and having a sliding connection with said lengths of the shoulder straps, and connections between the opposite lower extensions of the front all substantially as and for the purposes set forth.

3. A bathing form comprising a front hav-

ing at each side edge a shoulder strap, a side strap, and a rear extension, the shoulder straps being each provided with a loop through which its respective side strap may be extended, and the rear extensions being provided with straps to connect each with the opposite extension, and fastenings by which to secure the free ends of the several straps substantially as set forth.

10. 4. The bathing form herein described consisting of the front having at opposite sides of its upper end shoulder straps, provided below such ends with side straps and below

such side straps with rear extensions having loops or keepers and straps, the strap of each of such extensions being arranged and adapted to be passed through the keeper of the other, the shoulder straps having their rear lengths provided with loops or keepers through which the side straps may be passed and fastenings for the free ends of the several straps.

KATE HATCH.
